JOHAN S. FASTING, OF VALBY, NEAR COPENHAGEN, DENMARK, ASSIGNOR TO F. L. SMITH & CO., OF NEW YORK, N. Y., A CORPORATION OF NEW JERSEY.

GRINDING MILL.

Application filed April 4, 1923. Serial No. 629,301.

To all whom it may concern:

Be it known that I, JOHAN S. FASTING, a subject of the King of Denmark, residing at Monrads Alle 9, Valby, near Copenhagen, Denmark, have invented certain new and useful Improvements in Grinding Mills, of which the following is a specification, reference being had to the accompanying drawing, forming a part hereof.

10 This invention relates to grinding mills of the type commonly known as tube mills. As heretofore constructed such a grinding mill has a relatively long, cylindrical shell, sometimes of uniform diameter from end to end 15 and sometimes with one portion of greater diameter than the other portion, and supported at its ends by trunnions which rest in suitable bearing blocks. The trunnions are hollow in order to permit the admission at 20 the feeding end of the material to be ground and the discharge at the other end of the ground material. The cylinder, because of the bending moment to which it is subjected by reason of its considerable length and of 25 the weight of the charge of grinding bodies and material being ground, is sometimes supported between its ends by exterior supporting rings which rest upon suitable bearing rolls. A driving gear is also commonly applied to the cylinder by means of which the 30 cylinder may be rotated. In order to permit the progressive reduction of the material being ground, it is also common to erect within the cylinder one or more transverse partitions for the purpose of forming successive 35 grinding chambers to receive grinding bodies of different size or character, the partitions being provided with suitable openings through which the material may pass from 40 one chamber to the next. Among those skilled in the art, some of the disadvantages of such grinding mills are recognized. Because of the considerable length of the cylinder and the bending moment and other 45 stresses to which it is subjected, the cylinder must be of great strength and therefore must be constructed of relatively heavy metal, notwithstanding the fact that the metal is protected from wear internally by the lining of 50 the cylinder. This is particularly true of the cylinders which have portions of different diameters. The weight due to the strength of metal thus required adds to the power required for the operation of the mill without 55 proportionate results. The external bearing

rings and their supporting rolls quickly wear out of true, causing vibration and demanding increased power for operation. The end trunnions are necessarily of relatively small diameter and therefore limit to some extent 60 the size of the pieces of material to be ground which can be fed into the cylinder at the feeding end. The partitions are difficult of access for renewal and repair and in order to permit access (since the hollow trunnions 65 are too small to permit the passage of a man) there must be provided in each chamber a manhole, which necessarily weakens the shell somewhat, requiring still greater 70 strength of material, and brings about rapid wear internally because of the impracticability of protecting completely the manhole cover by lining. The considerable length of the cylinder gives importance to the longitudinal expansion and contraction of the cylinder 75 under the constantly varying temperatures, particularly in the grinding of hot cement clinker.

It has been found, in the present invention, that the disadvantages above mentioned in the operation of grinding mills, can be overcome largely and economy in operation effected by dispensing with the end bearing trunnions and supporting the mill by reduced bearings, of practicable diameter, between its ends. Usually, for a mill of standard length, it will be found sufficient to provide, between the extremities of the mill, two such bearings forming a middle or main grinding compartment, a primary grinding compartment overhung at one end, and a separating or screening compartment overhung at the other end. The several compartments communicate with each other through the hollow bearing members, which need not be of large diameter, since no large pieces of material will pass through them. The feed opening at one end and the discharge opening at the other end of the mill can be made 95 of such diameter as not only to permit the free introduction at the feeding end of material which is relatively coarse, but to permit the passage of a man so that the provision of a separate manhole in the cylindrical wall of either chamber is unnecessary. Since almost the entire end of each compartment or chamber is exposed, the bolts which hold the separating plates and liner plates at the discharge end of each 100

compartment are readily accessible, easy to inspect and easy to keep in order. The preliminary grinding chamber or compartment can be made of larger diameter than the other compartments so as properly to receive and crush the irregular and relatively large pieces of material which may be fed to it, such material being reduced in the preliminary grinding compartment to a substantially uniform and smaller size so that most of it will pass readily through the separator plate in the discharge end of the preliminary compartment. The bending moment of the middle and longer compartment of the mill is greatly reduced by the overhung preliminary grinding and separating or screening compartments and the weight of material employed for the construction of the mill is thus greatly reduced. The disadvantages due to expansion and contraction of the usual long mill, supported at its ends, are largely eliminated through the reduction in length even of the longer main compartment.

The invention will be more fully explained hereinafter with reference to the accompanying drawing, the single figure of which represents in longitudinal section, a grinding mill constructed in accordance with the invention.

In the embodiment of the invention illustrated in the drawing, the mill comprises a preliminary grinding compartment *a*, relatively short in length and of relatively large diameter, a main grinding compartment *b*, of such length as to effect the desired reduction of the material, and a relatively short supplemental grinding compartment *c*. The preliminary grinding compartment *a* comprises end plates *a'* and *a''*, the former provided with a central feed opening *a³* and the latter with a central discharge opening *a⁴*, and a cylindrical wall *a⁵*. Within the compartment and near its discharge end, is a perforated separator plate *a⁶* which has on its discharge side a discharge cone *a⁷* and substantially radial ribs or vanes *a⁸* which lift the reduced material which has passed through the perforations of the plate and discharge it upon the cone *a⁷* by which it is directed through the discharge opening *a⁴*.

The main grinding compartment *b* also comprises end plates *b'* and *b''*, the former provided with a central feed opening *b³* and the latter with a central discharge opening *b⁴*, and a cylindrical shell *b⁵*. It is further provided with a separating plate *b⁶*, which has a discharge cone *b⁷* and lifting ribs or vanes *b⁸* to effect the discharge of the produced material which passes through the separating plate *b⁶*. The compartment *b⁵* may also be provided externally with a gear ring *b⁹* by which the mill can be rotated.

The supplemental compartment *c* may

also comprise end plates *c'* and *c''*, the former having a central feed opening *c³* and the latter a central discharge opening *c⁴*. This compartment also has between the end plates a cylindrical wall *c⁵* and may have a separating plate *c⁶* provided with a discharge cone *c⁷* and elevating plates *c⁸*.

The two compartments *a* and *b* and the two compartments *b* and *c* are connected in pairs as shown by hollow bearing members *d* and *e*, which may be secured to the respective compartments by bolts as at *d'* and *e'*, such bearing members being hollow so as to permit the passage of material through the same, and being received in bearing blocks *f* and *f'* which may be mounted on suitable pedestals *f²* and *f³*.

A feed chute *g* may be provided for directing into the preliminary grinding drum *a* the material to be ground and the screening drum *c* may be provided with a discharge chute *g'*.

It will be observed that the feed opening *a³* of the preliminary grinding drum *a* can be made as large as may be desired so that the feeding of the material to be ground, even in relatively large pieces, will not be interfered with. Such material as has received, in the compartment *a*, the grinding necessary to permit it to pass

through the separating plate *a⁶*, will be raised by the vanes or ribs *a⁸* and, falling upon the cone *a⁷*, will be directed into and through the bearing member *d*, while, in like manner, the material which has been further reduced in the main grinding compartment *b* and has passed through the separating plate *b⁶*, will be raised and discharged through the hollow bearing member *e*. Finally, the material which may be further reduced in the screening drum *c* and passes through the separating plate *c⁶*, will be raised and discharged through the discharge opening *c⁴*.

It will be noted that the construction shown permits of the securing of the required strength without the employment of heavy metal, it being understood that the interior of each compartment is protected by the usual lining, not necessary to be shown. The feed opening of the preliminary drum or compartment can be made as large as desired; not only to permit the feeding in of material in relatively large pieces, but of such size as to permit the passage of a man, thereby doing away with the necessity of providing a manhole in the side wall of the drum, in order to give access to the interior for purposes of replacement and repair.

In like manner the openings of the bearing members *d* and *e* and, if necessary, of the discharge end of the supplemental compartment, can be made of such diameter as to permit the passage of a man.

I claim as my invention:

1. A grinding mill comprising a relatively long main grinding drum of relatively large diameter having end walls and a cylindrical wall, hollow bearing members 5 of relatively small diameter secured one to each end wall of the main grinding drum, supplemental drums of relatively large diameter each having an end wall secured to the outer end of one of the hollow bearing 10 members, the end walls of the drum being each provided with an opening communicating with the interior of a hollow bearing member, the hollow bearing members being adapted to serve as the means for supporting 15 the drums and to permit material treated to pass from one drum to another.
2. A grinding mill comprising a relatively long main grinding drum of relatively large diameter having end walls and 20 a cylindrical wall, hollow bearing members of relatively small diameter secured one to each end wall of the main grinding drum, supplemental drums of relatively large diameter and relatively short length each having 25 an end wall secured to the outer end of one of the hollow bearing members, a bearing block for each of the hollow bearing members, the end walls of the drums being each provided with an opening communicating 30 with the interior of a hollow bearing member, the hollow bearing members being adapted to serve as the means for supporting the drums and to permit material treated 35 to pass from one drum to another.
3. A grinding mill comprising a relatively long main grinding drum of relatively large diameter having end walls and a cylindrical wall, hollow bearing members of relatively small diameter secured one to 40 each end wall of the main grinding drum, supplemental drums of relatively large diameter and substantially equal relatively short length each having an end wall se-
- cured to the outer end of one of the hollow bearing members, a bearing block for each 45 of the hollow bearing members, the end walls of the drums being each provided with an opening communicating with the interior of a hollow bearing member, the hollow bearing members being adapted to 50 serve as the means for supporting the drums and to permit material treated to pass from one drum to another.
4. A grinding mill comprising a preliminary drum having end walls and a cylindrical wall, a main grinding drum having also end walls and a cylindrical wall, a supplemental grinding drum having end walls and a cylindrical wall, hollow bearing members 55 having their opposite ends secured respectively to the adjacent end walls of the preliminary drum and the main drum and the adjacent walls of the main drum and the supplemental drum, and bearing blocks for said bearing members, the preliminary drum having near its discharge end a separator plate with lifting ribs and a central discharge cone.
5. A grinding mill comprising a preliminary drum having end walls and a cylindrical wall, a main grinding drum having also end walls and a cylindrical wall, a supplemental grinding drum having end walls and a cylindrical wall, hollow bearing members 60 having their opposite ends secured respectively to the adjacent end walls of the preliminary drum and the main drum and the adjacent walls of the main drum and the supplemental drum, and bearing blocks for said bearing members, the preliminary drum having near its discharge end a separator plate with lifting ribs and a central discharge cone.

This specification signed this 15th day of March A. D. 1923.

JOHAN S. FASTING.
